UNITED STATES PATENT OFFICE.

JULIUS J. BRELL, OF NEW YORK, N. Y.

BUTTON-PLACING DEVICE FOR SEWING-MACHINES.

1,270,594.

Specification of Letters Patent. Patented June 25, 1918.

Application filed August 11, 1916. Serial No. 114,308.

To all whom it may concern:

Be it known that I, JULIUS J. BRELL, a citizen of the United States, and a resident of the city, county, and State of New York, (whose post-office address is 530 West 159th street, in said city,) have invented a new and useful Improvement in Button-Placing Devices for Sewing-Machines, of which the following is a specification.

The object of my invention is to provide a device of this class which will automatically and correctly set each button in turn for the needle of the sewing machine, so that buttons may be sewn by a machine, provided with my attachment, without any manual labor other than that necessary to put the needle over the place where the button is to be sewn, and to then start the operation of the machine. This, and other objects are accomplished by my invention, one embodiment of which is hereinafter more particularly described.

For a more particular description of my invention, reference is to be had to the accompanying drawings, forming a part hereof, in which—

Figure 1 is a side elevation of a button sewing machine provided with my improvement;

Fig. 2 is a plan view of the same;

Fig. 3 is a side elevation of the button attaching portion of my device, the view being shown on the opposite side from that on which Fig. 1 is taken; and

Fig. 4 is a plan view of the structure shown in Fig. 3, parts being broken away to clearly disclose the construction.

Throughout the various views of the drawings, similar reference characters designate similar parts.

My improved button placing device is attached to a suitable button sewing machine 2 of the conventional kind, in a manner which will be described below. In the particular embodiment of my invention, here illustrated, the machine 2 is adapted to sew through the holes of a button 3, and it is therefore necessary that these holes come into proper registration with the needle before the needle begins to operate, otherwise the needle will strike the solid portion of a button and thereby become bent or broken, and render the machine inoperative.

The buttons 3 which are to be attached by the sewing machine 2 come from a hopper or 55 magazine, not shown, of the conventional kind, and from thence slide down, right side up, this sliding taking place in a suitable chute 4, supported by any proper means, not shown, and this chute 4 has a grooved 60 face 5 on which are fixed suitable parallel plates 6 by screws or other suitable means, and between these plates there is a slot 7 through which the buttons may be observed and their progress checked by means to be 65 described below. As will appear, the mechanism is such that only one button is released for each reciprocation of the apparatus so that too many buttons cannot be fed so as to interfere with the operation of the device 70 and the sewing machine. Any suitable mechanism for permitting the buttons to be shifted one at a time may be employed, although the preferred one is here employed.

Near the bottom of the chute 4, and on 75 the base 5, is placed a suitable guide 8 which is held in position by screws or otherwise, and this guide carries a slide 9 which moves in the direction of its length, and not otherwise, under the influence of means to be 80 described. Under all conditions this slide 9 obstructs the passage in the chute 4, as it has two projections therein separated by the width of a button and one of these always blocks the chute so that buttons work 85 by one at a time, as shown in my U. S. Patent No. 1,212,181, dated January 16, 1917. This slide 9 carries a projecting cam 10 which is fixed thereto in any suitable way, as by a screw 11, and the free end of 90 this cam 10 passes over the plates 6 of the chute 4. This cam 10, while so passing, engages a lever 12 which is normally kept in contact with said cam by a spring 13 and this lever 12 is fulcrumed at 14 in any suitable way as by brackets and a pin, and at its free end it is provided with a pin 15 which projects into the slot 7, and close to the bottom thereof so as to prevent buttons from crowding the projections on the 100 slide 9 whenever the cam 10 is far enough under the lever and then the lower end of the lever 12 is held against this cam 10 by the tension of the spring 13. When this cam 10 is withdrawn, so that the spring 13 is 105 free to act, it raises the point 15 from the

chute so that some buttons may pass but not enough to interfere with the gate mechanism.

The means for giving a timely reciprocation to the slide 9 will now be set forth. The parts 16 rigidly attached to the slide 9 are adapted to be engaged by suitable set screws 17 and 18 respectively, which are mounted in suitable brackets 19 and 20, the former of which rises from the reciprocating frame 21 which has its extreme end guided by a perforation in a suitable bracket 22 fixedly mounted on the base 23 of the sewing machine, and its other end is connected by screws or otherwise to a reciprocating bent bar 24 which is guided by means of a suitable bracket 25 which is fixed to the bed 23 of the sewing machine. From this bar 24 rises the bracket 20. A suitable coil spring 26 connects this bar 24 with the bracket 25 so that under normal conditions this coil spring will cause the bar 24 and its frame 21 to remain in their rearmost positions, except when expelled from such positions and kept out of them by mechanism which will be described below. The rear part of the bar 24 has an adjustably connected and vertically disposed end 27 which may be engaged by any of three pins 28 fixed to the cam 29, which is timed so as to revolve one-third of a revolution for each button sewed on by the sewing machine. If a button has a different number of holes and the needle passes through a different number for this reason, more or less pins 28 may be had as required. The shaft 30, on which the cam 29 is mounted, is connected to the main shaft of the machine so as to revolve in unison therewith. Under normal conditions, the vertically disposed end 27 is kept out of the path of the adjustably mounted pins 28 by means of a pawl 31 which is connected to the frame or bracket 25 by means of a suitable coil spring 32, so that under normal conditions this pawl may engage one tooth of the ratchet 33 which is adjustably mounted on the bar 24. The pawl 31 is pivoted at 34 in a suitable bracket 35 which is secured to the bracket 25, and the free end of this pawl 31 is adapted to be engaged by an adjustably mounted lug 36 which is fixedly secured to a starting rod 37 which, at its lower end is connected to a chain 38, which in turn is connected to a foot pedal, not shown, by which the button placing mechanism may be actuated. The upper end of the starting rod 37 is flexibly connected to a lever 39 which forms a part of the presser foot lifting device for the sewing machine, so that the sewing machine and button placing mechanism are operated in unison when the foot pedal is pressed and the chain 38 and the rod 37 are actuated. An adjustably mounted lock 40 just

above the table or plate 23 and on the rod 37 limits the downward movement of this rod when the foot pedal is pressed as above set forth.

In addition to the lug 36 the rod 37 carries another lug 41 which is adjustably mounted thereon and this lug 41 carries a downwardly extending arm 42, the lower end of which is slotted to receive a suitable pin 43 on a bell crank lever 44 which is fulcrumed at 45 and has another arm provided with an adjustably mounted pin 46 which engages an adjustable link 47 which is in turn pivotally connected to another link 48 which is pivotally connected at its lower end to a small lever 49, the parts being so arranged and disposed that when the exposed end of the lever 49, shown in Fig. 2, is drawn toward the rear by the downward movement of the starting rod 37 the other or concealed end of this lever 49 is thrust forward in a manner and for a purpose which will be described below. By adjusting the pin 46 in the slot in the lever 44 it is possible to get any desired throw of the lever 49, as is obvious.

The frame 21 near the upright 19 is connected to a slide 50 which runs in a suitable button guide-piece 51 which is supported by a bracket 52 which runs to the head 53 of the sewing machine 2, so that the button guide-piece 51 is supported by the part in which the needle guide runs. This button guide-piece 51 has a suitable slot 54 near to the lower end of the slot in the chute 4 so that a button is delivered directly from the chute 100 to the slot 54 of the button guide and in front of the slide 50 which is reciprocated in this slot 54 when the frame 21 is reciprocated, as above described, so that a button 3 in this slot 54 is shifted by the slide 50 into the jaws 55 where it is gripped with a spring pressure and held against a stop 56, these jaws and the stop being properly held under a plate 57 and over a cam plate 58, and both of these plates are adapted to move 110 vertically because they are carried by a stem 59 mounted so as to reciprocate at the proper time in the goose neck 60 which forms a part of the machine 2. The stem 59 is connected by a pin 61 to the lifting 115 bar of the machine so that when this bar rises after the needle has completed its operation and when the foot pedal is depressed, it will raise the stem 59 with it and when it is depressed the stem 59 is lowered. 120 A suitable mechanism, as described in my said Patent No. 1,212,181, provides for the proper opening and closing of these jaws 55 and their raising and lowering, as above set forth.

From the foregoing, it is obvious that the holes or eyelets in the button 3 may fall in any position with regard to the needle 5

that they can occupy while the button is right side up and in a plane perpendicular to the direction of movement of the needle. It does not follow that these be so that their holes are in proper registration with the path of the needle. To put them in such registration, the following mechanism is employed:—

The lever 49 is pivotally connected to a sliding bar 62 which moves in a suitable guide 63, which has a slot 64 in its upper surface, through which protrudes a pin 65 that is connected to a spring 66 which is also connected to a corresponding pin 67 mounted on the guide 63, so that the bar 62 is normally held in its rearmost position through the action of this spring 66 and is shifted forward by the downward movement of the starting rod 37 through the mechanism described below. The stop pin 68 limits this rearward movement as shown in Fig. 4. This stop pin 68 also carries one end of a suitable coil spring 69 the other end of which is secured to a pin 70 and extends from a small pivoted link or clevis 71 mounted on the bar 62, the forward end of which is pivotally connected to a bent arm 72 and to this arm 72 is pivotally secured a finger 73, the forward end 74 of which is pointed and adapted to engage the button and turn the same on its rearward movement, never on its forward movement, so that when the button 3 leaves the finger 73 the hole in the button is sure to be in proper registration for the needle, and as all holes stand in a fixed relation to each other in each button, it is obvious that all holes are properly placed for the action of the needle. It is to be noted that before the finger "73" leaves the button, it has rotated the button a predetermined amount so that when the finger 73, on its rearward movement, frees itself from the hole in the button which it has engaged, the button has been rotated a certain distance so that its holes are properly positioned. To cause the point 74 to act only on its return movement and never on its forward movement a projection 75 is secured to the top thereof and the free end of this projection 75 rides over the top of a cam 76 fixed to the frame 21 as shown in Figs. 3 and 4. The button turning mechanism is so arranged and timed in its movements so that when the finger 73 moves forward toward the jaws 55, these jaws are not holding a button between them. During the complete forward movement of the finger 73, the projection 75 on said finger does not contact with the cam 76. After the finger 73 has moved to the limit of its forward movement, a button is then thrust between the jaws 55 by means of the slide 50 on the frame 21. As the slide 50 moves toward the jaws 55 to force a button between them, the

frame 21 is, of course, correspondingly moved, and when the frame 21 so moves, it causes the cam 76 to be passed beneath the projection 75 whereby the finger 73 is lifted so that the pathway of the button, as it is thrust between the jaws 55, is not obstructed by the finger 73. As the frame 21 continues its movement, toward the right as viewed in Figs. 3 and 4, the cam 76 passes entirely beneath the projection 75, thus allowing the projection 75 to descend and correspondingly allowing the finger 73 to descend on the face of the button held between the jaws 55. The jaws then descend so that when the finger 73 moves rearwardly and rotates the button, the projection 75 passes under the cam 76. The jaws 55 continue their downward movement until they reach their lowermost position, when the button is sewed in place by the needle in the usual manner.

The guide 63 has a projection 80 secured to it, and from this projection 80 extends a spring guide 77 which rests on the finger 73 to guide the same and to resist improper movement of the finger.

Operation.

In view of the foregoing, the operation of my improved attachment will be readily understood. Assuming the parts to be ready and the buttons in the hopper, they come down the chute 4, as above described, and one at a time are let into the slot 54 of the guide 51. The first button should be put in place by hand, or otherwise, so that the machine 95 will not sew when no button is in position. After the first button has been sewn in place the foot treadle is pressed and thereby raises the jaws 55 to the level of the slot 54 and frees these jaws of the button which has 100 been attached to the fabric as described in my said application. When the jaws are so raised the slide 50 is actuated to force another button between these jaws and then they are lowered. When these jaws are 110 raised and before a button has been inserted between them, the finger 73 goes forward and is then elevated and lowered as heretofore described and when lowered this finger is drawn backward and then the point 74 115 of this finger wipes the button and turns it, if any turning is required, until it is true and then the button gets free of the finger as it is lowered in the jaws 55, and leaves the same, as the guide 77 keeps the point 74 120 from reaching the lowest button level as above set forth.

This cycle is repeated as long as the machine sews buttons. Each button 3 is fed as above described, one at a time down the 125 chute 4 and then the frame 21 is reciprocated rearwardly and then forwardly once for each button that is sewed, the forward

reciprocation being caused by the action of a pin 28 and the rearward reciprocation by the action of the spring 26. The pawl 31 engages with the ratchet 33 in time to prevent a backward movement when the pedal is not depressed. The starting bar 37 is raised as before the sewing mechanism is started. The button feeding mechanism is actuated through the screws 17 and 18 so as to shift the slide 9 and the parts connected thereto, while the button 3 is being sewed so that another button will be ready for the next operation of the machine.

It will be understood that the machine is started from two pedals neither of which is shown. One, as above set forth, actuates the button feeding and placing device, the other starts the sewing machine. These pedals are pressed successively, first the button placing pedal and after it is restored, the sewing machine starting pedal.

Although I have shown and described one embodiment of my invention, it is obvious that it is not restricted thereto but is broad enough to cover all structures that come within the scope of the annexed claims.

Having thus described my invention, what I claim is:—

1. In a machine of the class described, means for holding a button, means for turning said button in said holder, means for reciprocating said button-turning means forward and away from the button holder, means for elevating the button-turning means when said means has reached its forward position and means for lowering said button-turning means whereby said button-turning means rotates the button on its rearward movement.

2. In a machine of the class described, means for holding a button in the path of a needle, and means for turning the button in said holder, said means comprising a pivoted finger provided with a point at its end, means for reciprocating said finger, a projection extending from said finger, a cam and means for reciprocating the same to cause it to engage the projection so that when the finger reaches its forward position it is raised and then lowered to wipe the button on its return movement and to turn the same so that the holes in said button are in proper registration with the path of the needle.

3. In a machine of the class described, means for holding a button in the path of a needle, a reciprocating finger for engaging said button while so held and rotating the same, means for reciprocating said finger, a projection on said finger, means for engaging said projection when the finger has reached its forward position, to elevate and hold said finger free from contact with said button and means for causing said finger to

engage and rotate the button on its rearward movement.

4. In a machine of the class described, means for holding a button, a reciprocating finger for rotating said button in its holder, a laterally extending projection on said finger, a cam for engaging said projection when said finger reaches its forward position and lifting said finger, said cam adapted to become disengaged from said projection on the rearward movement of said finger, and means for causing an engagement of said finger with the button to rotate the same on the rearward movement of said finger.

5. In a machine of the class described, means for sewing on buttons, means for supplying buttons to said button sewing means, a pair of jaws for holding a button received from said button supplying means between said jaws, a reciprocating finger moving above said button while held in said jaws, a downwardly projecting integrally formed point on said finger for engaging a button while held in said jaws and rotating the same, and means for engaging said finger to lift the same when the finger reaches the limit of its forward movement, and means for causing said finger to engage and rotate the button on its rearward reciprocation.

6. In a machine of the class described, means for sewing on buttons, a chute for delivering buttons to said button sewing means, means for individually delivering a button to said button sewing means comprising a pivoted finger and a cam movable beneath said finger, means for reciprocating said cam, said means comprising a reciprocating frame with projections to engage the cam, a bracket in which a portion of said frame is mounted, means for reciprocating said frame in one direction comprising a rotatable shaft with radially extending projections for contacting with a portion of said frame and means for reciprocating said frame in another direction, said means comprising a spring extending from said frame to the bracket in which said frame is mounted.

7. In a machine of the class described, a button chute for delivering buttons individually to button attaching means, a pair of jaws for holding the buttons delivered by said chute, a slide for forcing the buttons delivered by the chute between said jaws, a reciprocating finger for moving between the jaws, and means for elevating the finger clear of the button when the finger has reached the limit of its forward movement and causing the finger to contact with and rotate the button on its rearward movement.

8. In a machine of the class described, means for sewing on buttons, means for feed-

ing buttons to the button sewing mechanism, said button feeding means including, a bracket, a bar slidably mounted therein, a spring adapted to draw said bar in one direction, a pawl adapted to hold said bar in its forward position against the tension of the spring, a rotatable shaft, a plurality

of radially extending projections on said shaft for intermittently engaging and moving the bar forward against the tension of the spring and means for releasing the pawl so that the bar may be drawn rearwardly by said spring.

JULIUS J. BRELL.
